Primary Examiner — Sheryl Lane*Assistant Examiner* — Aula Soroush(74) *Attorney, Agent, or Firm* — 3M Innovative Properties Company(57) **CLAIM**

The ornamental design for a design for inhaler, substantially as shown and described.

DESCRIPTION

FIG. 1 is a front elevational view depicting an inhaler of our design in a first configuration;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front elevational view depicting an inhaler of our design in a second configuration;

FIG. 8 is a rear elevational view thereof;

FIG. 9 is a left side elevational view thereof;

FIG. 10 is right side elevational view thereof;

FIG. 11 is a top plan view thereof; and,

FIG. 12 is a bottom plan view thereof.

The broken lines in the drawings illustrate portions of the inhaler that form no part of the claimed design.

1 Claim, 6 Drawing Sheets(56)
